UNITED STATES PATENT OFFICE.

HANS HANSEN, OF BROOKLYN, NEW YORK, ASSIGNEE TO EASTERN FLEXIBLE CONDUIT COMPANY, OF BROOKLYN, NEW YORK, A CORPORATION OF NEW YORK.

FLEXIBLE ELECTRICAL CONDUIT.

1,285,138.

Specification of Letters Patent Patented Nov. 19, 1918.

Application filed March 9, 1916. Serial No. 83,193.

To all whom it may concern:

Be it known that I, HANS HANSEN, a subject of the King of Norway, residing at Brooklyn, in the county of Kings and State of New York, have invented new and useful Improvements in Flexible Electrical Conduits, of which the following is a specification.

My invention relates to flexible non-metallic electrical conduit, and its object is to provide such a conduit which shall be non-collapse, non-extensible, and have a smooth interior surface, and at the same time be economical to manufacture.

Experience in the use of conduits of this particular class has shown that it is essential to provide in the structure a resilient member or members arranged transversely to the axis of the conduit to form a supporting means to prevent the collapse or flattening of the tubing when flexed in installing the same around curves and bends, and to maintain a cylindrical form of conduit under the usual conditions of installation and use. A helical member composed of resilient material has usually been employed for this purpose, sometimes surrounding a tubular structure and sometimes inclosed within it. In the former case the turns or convolutions of the helical member must not be widely separated in order to support the inner tube against collapse. In order to accomplish this it has been customary to wind the helix so that the adjacent turns or convolutions are in close contact and form practically a continuous wall. If this is not done, and the turns are spaced apart, they may crowd together in places and become widely separated in others, leaving in the latter case no suitable support for the inner tube and thereby rendering it collapsible and worthless for the purpose designed. My aim is to produce a conduit in which the helical member incloses an inner tube

formed of a longitudinally folded strip, and where the turns of the helical member are separated but are locked and permanently held in a fixed relation to each other, thereby insuring the required support and greatly reducing the cost of material and labor in the manufacture of the conduit.

I accomplish these objects by inclosing a longitudinally folded strip of closely woven fabric within a supporting helix of semi-flexible material the convolutions of which

are spaced apart, and interweaving with the convolutions of the helix a series of flexible longitudinally laid members also substantially spaced apart. The structure thus formed is then treated with the usual fire-proofing and waterproofing compounds, in the usual manner, and if desired may be inclosed in a braided or woven exterior jacket, though this latter is not essential.

In my preferred form of conduit I employ a pair of helices of paper twisted into a circular cross section wound simultaneously closely adjacent each other, and interweave the longitudinal members, also laid in pairs, with each pair of convolutions instead of singly. By embodying a longitudinally folded flat fabric lining, I am able to interweave the helices and longitudinal threads loosely and still prevent seepage of the compound to the interior of the tube.

In the accompanying drawing in which like numerals of reference indicate corresponding parts in the various figures thereof, Figure 1 is a plan view of my preferred type of conduit partly broken away to show the construction. Fig. 2 is a similar view showing a loose woven lining with paper backing. 3 is the flat fabric of close woven elements 8 folded longitudinally about a mandrel with the edges 4 and 5 abutting to form the lining of the conduit. 6 represents the supporting helices, and 7 the longitudinal interwoven threads. 9 is the paper backing.

The manufacture of the structure described presents no novel problem, and may be accomplished by machinery well known to those skilled in the art of conduit manufacture. Detailed description of such machinery and the related processes is therefore deemed unnecessary.

What I claim and desire to secure by Letters Patent is:

1. A conduit of the character described comprising a lining, a helix of semi-flexible material inclosing said lining, the convolutions of the helix being separated by substantial unfilled spaces, and a series of longitudinally disposed flexible members interwoven with said convolutions and maintaining the spacing between the convolutions.

2. A conduit of the character described comprising a longitudinally folded flat fabric lining, a helix of semi-flexible material inclosing said lining with the convolutions

separated by substantial unfilled spaces; and a series of longitudinally disposed flexible members interwoven with said convolutions and maintaining the spacing of the convolutions.

3. A conduit of the character described comprising a lining, a helix composed of a set of parallel semi-flexible strands arranged in parallel relation, the convolutions of the set being separated by substantial spaces, and a series of longitudinally dis-

posed flexible members interwoven with the convolutions of the helix.

In testimony whereof I have hereunto set my hand in presence of two subscribing 15 witnesses, this sixteenth day of February, 1916.

HANS HANSEN.
